UNITED STATES PATENT OFFICE

113,681

DESIGN FOR A DISPLAY TRAILER

William Lee Parsons, Jr., Omaha, Nebr.

Application May 21, 1938, Serial No. 77,326

Term of patent 7 years

To all whom it may concern:

Be it known that I, William L. Parsons, Jr., a citizen of the United States, residing at Omaha, in the county of Douglas and State of Nebraska, have invented a new, original, and ornamental Design for a Display Trailer, of which the following is a specification, reference being had to the accompanying drawing, forming a part thereof.

In the drawing Figure 1 is a side elevational view of a display trailer showing my new design,

and Figure 2 is a view showing the reverse side of the same, the rear sloping portion of the trailer being plain. Also the rounded front portion is provided with two flat panes of glass inclined downwardly and forwardly.

Figure 3 is a front end view of the display trailer.

I claim:

The ornamental design for a display trailer, as shown and described.

WILLIAM LEE PARSONS, JR.
